(57) **CLAIM**

The ornamental design for a surface configuration of a vehicle and/or toy body, as shown and described.

DESCRIPTION

FIG. 1 is a perspective view of a first embodiment of a surface configuration of a vehicle and/or toy body according to our novel design;

FIG. 2 is a front view of the first embodiment of the surface configuration of a vehicle and/or toy body according to our novel design;

FIG. 3 is a left view of the first embodiment of the surface configuration of a vehicle and/or toy body according to our novel design;

FIG. 4 is a right view of the first embodiment of the surface configuration of a vehicle and/or toy body according to our novel design;

FIG. 5 is a rear view of the first embodiment of the surface configuration of a vehicle and/or toy body according to our novel design;

FIG. 6 is a top view of the first embodiment of the surface configuration of a vehicle and/or toy body according to our novel design;

FIG. 7 is a perspective view of a second embodiment of the surface configuration of a vehicle and/or toy body according to our novel design;

FIG. 8 is a front view of the second embodiment of the surface configuration of a vehicle and/or toy body according to our novel design;

FIG. 9 is a left view of the second embodiment of the surface configuration of a vehicle and/or toy body according to our novel design;

FIG. 10 is a right view of the second embodiment of the surface configuration of a vehicle and/or toy body according to our novel design;

FIG. 11 is a rear view of the second embodiment of the surface configuration of a vehicle and/or toy body according to our novel design;

FIG. 12 is a top view of the second embodiment of the surface configuration of a vehicle and/or toy body according to our novel design;

FIG. 13 is a perspective view of a third embodiment of the surface configuration of a vehicle and/or toy body according to our novel design;

FIG. 14 is a front view of the third embodiment of the surface configuration of a vehicle and/or toy body according to our novel design;

FIG. 15 is a left view of the third embodiment of the surface configuration of a vehicle and/or toy body according to our novel design;

FIG. 16 is a right view of the third embodiment of the surface configuration of a vehicle and/or toy body according to our novel design;

FIG. 17 is a rear view of the third embodiment of the surface configuration of a vehicle and/or toy body according to our novel design;

FIG. 18 is a top view of the third embodiment of the surface configuration of a vehicle and/or toy body according to our novel design;

FIG. 19 is a perspective view of a fourth embodiment of the surface configuration of a vehicle and/or toy body according to our novel design;

FIG. 20 is a front view of the fourth embodiment of the surface configuration of a vehicle and/or toy body according to our novel design;

FIG. 21 is a left view of the fourth embodiment of the surface configuration of a vehicle and/or toy body according to our novel design;

FIG. 22 is a right view of the fourth embodiment of the surface configuration of a vehicle and/or toy body according to our novel design;

FIG. 23 is a rear view of the fourth embodiment of the surface configuration of a vehicle and/or toy body according to our novel design; and,

FIG. 24 is a top view of the fourth embodiment of the surface configuration of a vehicle and/or toy body according to our novel design.

The broken lines included depict environment and are not part of the claimed design.
